UNITED STATES PATENT OFFICE.

GEORGE B. COCKER, OF GASTONIA, NORTH CAROLINA.

STOP CONTROL MEANS FOR TEXTILE MACHINERY.

Application filed July 18, 1925, Serial No. 44,466. Renewed October 10, 1928.

This invention relates to machines or apparatus such as "beaming" or "balling warpers" employed in the textile industry to unwind yarns from spools or bobbins and to mass them into a form convenient for use in looms, or in handling during bleaching, dyeing, etc., and, more specifically speaking, has reference to stop control means instrumental in automatically 10 causing stoppage of the apparatus in the event of breakage or rupture of any one of the yarns. Of such means, two types are generally employed, one operating mechanically, and the other electrically; and 15 it is with the latter type that this invention is more particularly concerned. In devices of this sort as heretofore constructed, considerable difficulty and trouble has been experienced on account of their inability 20 to compensate for abnormal slack in the yarns due to uneven initial winding of the spools or bobbins from which the yarn is drawn, or the accidental formation of folds or gatherings therein, so that stoppage of the 25 apparatus was often brought about without any breaks or ruptures actually occurring in the yarns.

Amongst the objects of my invention are to overcome the difficulty noted and to correct 30 various structural deficiencies heretofore prevalent in electric stop control devices so as to render them immune against easy derangement, and thoroughly reliable in operation.

One way in which this desideratum may be conveniently attained will be readily apparent from the detailed description which follows of a typical embodiment of my invention, the appended claims serving to define 40 those features which I believe to be entirely new and novel, and wholly within the scope of the present improvements.

With reference to the drawings, Fig. I is a perspective view of a portion of a warping 45 apparatus showing my improved stop control means in association therewith.

Fig. II is a fragmentary perspective illustration of the stop control means viewed from a different angle.

Fig. III is a staggered sectional view taken as indicated by the arrows III-III in Fig. I.

Fig. IV is a perspective view of the movable member of the stop control means detached from the apparatus; and

Fig. V is a fragmentary detailed sectional

view taken as indicated by the arrows V-V in Fig. II.

The portion of apparatus herein illustrated is ordinarily known as a "creel", 60 and will be observed as of standard construction generally in that it comprises a series of spaced parallel uprights or posts 1, 2 which are grouped in pairs, each pair supporting between them, a vertical series 65 of spools or bobbins 3 wherefrom the yarn is unwound in the process of warping after a well known manner. The uprights or posts 1, 2 are, in the present instance, made of some dielectric material, preferably well 70 seasoned wood; and their opposite ends are engaged in socket fittings 4 secured to opposed upper and lower headers of which only the top one is shown at 5 in Fig. I, tie rods 6 being employed to hold the frame 75 parts rigidly in assembly, as shown. The trunnions 7 of the spools or bobbins 3 are detachably engaged in stirrup brackets 8 (see Fig. III) which are accommodated in longitudinal recesses 9, 10 respectively 80 formed in the inner sides of the uprights 1, 2 at the rear. The usual opposed electrical conductor strips 11, 12 are in each instance attached in spaced relation to the right angled walls of a longitudinal recession 13 85 formed in the outer face of the post 1 adjacent the recess 9 previously referred to; and each of said posts 1 (except the last one at the left of Fig. I) has secured to it in a convenient manner, a co-extensive metallic rod 14 about which the yarns are passed in leaving said spools.

As is usual in electric stop systems of the type referred to, with each spool or bobbin 3 is associated a contact control means 95 adapted, upon rupture of the yarn, to automatically establish or close the circuit between the conductor bars or strips 11, 12 and thus effect energization of the magnet or other electric device (not shown) relied 100 upon to bring about stoppage of the apparatus. As shown, the circuit closing means of my invention comprises a movable member or drop wire 15 (as it is ordinarily termed technically) adapted to be normally 105 supported in suspension by the yarn passing from the corresponding spool or bobbin 3, and a fixed guide element 16 embodying yarn engaging ledges 25, 26 which cooperate with the movable member 15 in the manner hereinafter explained while said guide element 16 is secured to the post 1 by a

screw 28. The movable member 15 will be observed as of right angled configuration, characterized by a comparatively short segment 17 from which extends, laterally, a longer segment 18 provided with a closed eye 19 for passage of the yarn. To obtain the advantages of combined strength and lightness in the construction of the member 15, I employ a single strand of wire wherein the eye 19 is formed centrally by double superposed looping in a manner obvious from Fig. IV. Beyond the eye 19 the ends of the wire strand are converged as at 20, 20 to a point of meeting, and from thence extend in contiguous parallelism to their terminals which are bent over as at 21, 21 to embrace a bearing sleeve 22, see Fig. III, the sleeve 22 being held in place by reason of having its opposite ends turned over facing washers 23. As an attaching means I use a screw 24 in mounting each of the members 15 to the upright 1, said screw passing through an aperture in the conductor strip 11. By this construction it will be seen that the member 15 is accorded free pivotal movement on the stud screw 24 to the avoidance of any binding action as sometimes occurs with the conventional form of drop wire in which a terminal curl alone serves as a pivot bearing.

In order to insure good electrical contact at the regions of pivotal attachment of the members 15, I offset the conductor strip 11 at these regions, preferably by slight outward bowing or bulging as shown to best advantage at 11^a in Fig. V. By resorting to this expedient and choosing a hard quality of brass as the material for the strip 11 (instead of soft copper as generally customary), the bulge 11^a may in each instance be made to exert just sufficient yielding spring pressure against the contiguous ends of the bearing 22 of the member 15, to predetermine metallic contact without inducing binding, such pressure being easily regulatable by partial turning of the screw 24. The arrangement just described obviates the necessity for depending upon contact as between the shank of the screws 24 and the edge of the receiving hole in the strip 11, for the purpose of electric continuity, as has generally been customary heretofore, and which, on account of its uncertainty, has given rise to considerable difficulty in actual practice.

In operation of the apparatus, the members 15 will normally occupy the upright position shown in Fig. I under the constant pull of the yarn, and be free to bob or vibrate back and forth in responding to incidental fluctuations in tension. When in the normal position, it is to be particularly noted that the center of gravity of the member 15 is almost directly above the pivot 24

so that but a very light and negligible drag is imposed on the arm. This feature is of extreme importance and greatly reduces the power required in operating equipments of large capacity where countless yarns are warped at one time. In the event of abnormal slack due to any of the causes heretofore mentioned or to overrunning of the spools upon stoppage of the apparatus, the members 15 will immediately fall under the influence of gravity, to a position such as shown in Fig. II with resulting formation in each instance by cooperation of the ledges 25, 26 on the fixed element 16, of a diverted saddle loop L by which the member 15 is supported and held from closing the circuit across the strips 11, 12. Owing to the liberal range of angular movement accorded the member 15 (which will be noted as substantially 90°) ample yarn can be absorbed in the loop L to compensate fully for any of the contingencies named without resulting in circuit closure. Upon rupture of the yarn, the member 15 will simply drop to the full extent determined by engagement of its angle corner with the metallic strip 12 to close the electric circuit and cause automatic stoppage of the apparatus in the known manner. The liberal proportioning and rounding of the eye 19 of the member 15 as shown renders the operation of rethreading very easy of accomplishment, and also facilitates free positional adjustment of the yarn at all times to the avoidance of any restraint thereupon.

Having thus described my invention, I claim:

1. The combination in electric stop control means for textile machinery of spaced current conductors; a pivotally-suspended gravity-actuated stop control member in circuit with one of said conductors, said member being formed from a single strand of wire to provide a yarn-eye with the terminal ends relatively-angled to embrace a bearing sleeve; and a fixed guide in close proximity thereto having spaced ledges functional to determine formation of a diverted slack-compensating saddle-loop in the yarn whereby the stop control member is normally floatingly supported and adapted to accommodate abnormal slack in individual yarns without stopping the machine.

2. A gravity control member for stop motions of textile machinery constructed from a single strand of wire with a yarn eye formed centrally of the strand, the ends of the latter extended in contiguous parallelism from the eye, and the terminals of said ends curled for pivotal mounting.

3. A gravity control member for stop motions of textile machinery constructed from a single strand of wire with a closed yarn eye formed by double superimposed looping centrally of the strand, the ends of

the latter extended in contiguous parallelism from the eye, and the terminals of said ends curled for pivotal mounting.

4. A gravity control member for stop motions of textile machinery including a part formed from a single strand of wire looped centrally to form a yarn eye, its ends extended in contiguous parallelism beyond the eye and finished with terminal curls; 10 and a bearing sleeve embraced by said curls.

5. A gravity control member for stop motions of textile machinery including a part formed from a single strand of wire looped centrally to form a yarn eye, its ends 15 extended in contiguous parallelism beyond the eye and finished with terminal curls; a bearing sleeve embraced by said curls; and

face washers over which the ends of the sleeves are flanged.

6. In electric stop control means for textile machinery, the combination of a pivotally mounted control member, and a current conducting strip pierced to receive a pivot screw for the control member, said strip being offset at the region of the pivot to exert 25 slight yielding pressure, regulatable by the screw, against the pivot bearing of the control member for the purpose of insuring good electrical contact.

In testimony whereof, I have hereunto 30 signed my name at Gastonia, North Carolina, this 11th day of July, 1925.

GEORGE B. COCKER.
